The ornamental design for a head covering hood, as shown and described.

DESCRIPTION

FIG. 1 is a front perspective view of a head covering hood showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view thereof, with the mouth cover flap in an open position.

The person's face and shoulders shown in broken lines in FIGS. 1 and 8 are shown for illustrative purposes only and form no part of the claimed design. The broken lines overlapping the claimed design in FIGS. 1-5 and 8 represent conventional stitching.
